UNITED STATES PATENT OFFICE.

RICHARD BARKER, OF LONDON, COUNTY OF MIDDLESEX, ENGLAND.

APPARATUS FOR EXTRACTING GOLD AND SILVER FROM THEIR ORES.

SPECIFICATION forming part of Letters Patent No. 276,997, dated May 8, 1883.

Application filed April 5, 1883. (No model.)

To all whom it may concern:

Be it known that I, RICHARD BARKER, a subject of the Queen of Great Britain and Ireland, residing at London, in the county of Middlesex, England, mining-engineer, have invented certain new and useful Improvements in Apparatus for Extracting Gold and Silver from their Ores, of which the following is a specification.

- 10 My invention relates to improvements in extracting gold and silver from their ores by the combined action of electricity, mercury, and water applied in the manner and by means of apparatus as hereinafter described.
- 15 For the purpose of my invention I provide a table in which I arrange a number of riffles, vats, troughs, or other suitable vessels, insulated or not, and made of iron, wood, porcelain, ebonite, gutta-percha and its products, earthenware, (glazed or unglazed,) or any other suitable material. A current of electricity is then applied to the water by one or more suitable cathodes and anodes placed therein. The electricity is allowed to flow from one pole to the other, thereby producing an agitation on the surface of the mercury and causing it to absorb the gold and silver. I cause, by any convenient means, a stream of water to pass over or through the table, vat, trough, or other vessel containing the ore to be operated upon, one object being to wash away the waste ore and the other to furnish a continuous supply of hydrogen and oxygen to the ore. To assist the agitation on the surface of the mercury I 35 provide one or more stirrers or agitators.

In order that my invention may be readily understood and carried into effect by any competent person experienced in the art or process to which it relates, I proceed to describe the same with reference to the accompanying drawings.

Figure 1 is a plan of a riffle, vat, or trough to which my improvements are applied, the

stirrers, however, being removed for sake of clearness. Fig. 2 is a cross-section of a riffle, 4 vat, or trough, showing the position of the main cathode and the stirrer, the branch cathode being shown in the water, but above the mercury. Fig. 3 is a cross-section of a riffle, vat, or trough, showing the position of the main anode and stirrer, the branch anodes being shown in the water and above the mercury.

R is the riffle, vat, or trough, along one side of which the main anode A is laid. From this anode A branch anodes A' A' pass into the water and across the riffle. On the opposite side of the riffle is laid the main cathode C, from which branch cathodes C' C' extend into the water and across the riffle in the opposite direction, and sufficiently far away from the branch anodes so as not to touch one another.

S is a stirrer to assist agitation on the surface of the mercury.

H is the terminal of the branch anodes, and H' the terminal of the branch cathodes.

x is the wire from the battery or other source of electricity, and y is the return-wire.

Having now described my invention, what I claim, and desire to secure by Letters Patent, is—

In apparatus for extracting gold and silver from their ores by the combined action of electricity, mercury, and water, the cathodes and anodes arranged to extend across the riffle, vat, or trough, and to lie in the water and above the mercury, substantially as described and shown, and for the purpose set forth.

In witness whereof I have hereunto signed my name in presence of two subscribing witnesses.

RICHARD BARKER.
